UNITED STATES PATENT OFFICE.

EDWARD J. BROOKS, OF EAST ORANGE, NEW JERSEY.

DESIGN FOR A SNAP-SEAL SHACKLE.

SPECIFICATION forming part of Design No. 27,822, dated November 9, 1897.

Application filed November 27, 1894. Serial No. 530,185. Term of patent 7 years.

To all whom it may concern:

Be it known that I, EDWARD J. BROOKS, a citizen of the United States of America, and a resident of East Orange, in the State of New Jersey, have invented and produced a new, useful, and original Design for a Snap-Seal Shackle, of which the following is a specification, reference being had to the accompanying drawing, which represents a side view of a snap-seal shackle.

The leading feature of this design is a peculiarly-shaped shackle end having the characteristics hereinafter specified, including a flat serpentine portion immediately adjacent to the snap-catch.

In the drawing, A A represent two shackle ends of one and the same shape, and B the body of the shackle uniting said ends. Each

of said shackle ends comprises an oblique portion 1, an arc-shaped portion 2, a straight portion 3, and a serpentine portion 4, united with each other and with the body of the shackle by curves, while the several undulations of said serpentine portion are curvilinear. The shackle-body B is bowed and the pair of shackle ends A project therefrom as converging radii.

Having thus described the said design, what I claim is—

The design for a snap-seal shackle, substantially as shown and described.

EDWARD J. BROOKS.
